[57] ABSTRACT

A sheet stacking apparatus removes sheets as they are advanced one at a time on a belt or other conveyor from a remote point toward a stack receiver, by means of a series of fluid nozzles positioned in a common plane which overlies the conveyor and the stack receiver. By directing air downwardly and along the upper surfaces of the sheets on the conveyor, they are elevated by Bernoulli's principle into non-contacting closely spaced relation to the nozzles and substantially parallel to the plane of the nozzles. The plane of the nozzles is inclined downwardly toward the stack from the conveyor so that the sheets slide toward the stack receiver by gravity while maintaining their non-contacting spaced relation with the nozzles. Fluid flow to those nozzles which overlie the stack is automatically momentarily cut off when the sheet overflies the stack and the sheet then falls onto the stack cushioned by the air trapped between the upper side of the stack and lower side of the sheets.

SHEET STACKING APPARATUS

BACKGROUND OF THE INVENTION

In the material handling field, sheet stackers which accumulate sheets one at a time from a conveyor and automatically lower the stack support to maintain the uppermost sheet at a constant vertical elevation are known. Sheet handling means which support sheets from above by fluid flow through noncontacting nozzles operating on Bernoulli's principle are also known. Examples may be found in the U.S. Pats. to Forrester No. 3,054,613, Walton et al No. 3,168,307, Stanley No. 3,198,499, Hori et al No. 3,219,340, Robinson No. 3,220,723, Olsson et al No. 3,438,668 and Albright et al No. 3,411,770. This principle is useful wherever the sheet being handled would be adversely effected by contact with vacuum grippers or the like and one example of such material is freshly silvered glass.

BRIEF SUMMARY OF THE INVENTION

In accordance with the present invention, a transfer means operating on Bernoulli's principle transfers sheets one at a time from a conveyor to a stack. A plurality of nozzles are arranged to overlie the conveyor and the stack support and are arranged in a common plane which is inclined to the horizontal with the higher end over the conveyor and the lower end over the stack support. A fluid such as air under positive pressure is fed to all nozzles to elevate sheets from the conveyor into closely spaced but non-contacting relation to the nozzles. Due to the inclined plane of the nozzles, the sheets then slide by gravity in a plane parallel to the plane of the nozzles until they overlie the stack receiver. At this point in time, the flow of air to those nozzles which are supporting the sheet over the stack is momentarily cut off and the sheet permitted to fall by gravity onto the uppermost sheet of the stack and its fall is cushioned by the blanket of air trapped between the under surface of the sheet and the uppermost sheet of the stack.

BRIEF DESCRIPTION OF THE DRAWINGS

FIG. 1 is a diagrammatic side elevational view of the overall apparatus of the present invention;

FIG. 2 is a top plan view of the apparatus shown in FIG. 1;

FIG. 3 is a side elevation partially in section of one of the nozzles; and

FIG. 4 is a diagrammatic showing of one means for automatically maintaining a constant elevation of the uppermost sheet of the stack by lowering the stack support in step-wise fashion in response to the addition of each successive sheet to the stack.

DETAILED DESCRIPTION OF THE DRAWINGS

Referring first to FIG. 1, a sheet stack supporting and level maintaining means is identified generally by the reference numeral 10. A belt conveyor 12, driven by means not shown, conveys the sheets 14 to be stacked one at a time in the direction indicated. A transfer means of the non-contacting type is indicated generally at 16 and is effective to transfer the sheets 14, without contacting them, from a conveyor 12 to the stack receiving means 10.

The sheet transfer means includes a plurality of nozzles 18 supported on the underside of a common hous-

ing 20. The housing 20 includes a pair of separate manifolds 20A and 20B so that the flow of air to the left hand group of nozzles 18 may be controlled separately from the others. Air under pressure is supplied to both manifolds from a blower 22 and a closed conduit 24. A valve 26 is positioned in the conduit 24 to permit interruption of fluid flow to the manifold 20A without disturbing flow to the manifold 20B.

By reference to FIG. 2 of the drawings, it will be appreciated that the manifolds 20A and 20B are of substantial horizontal extent and in fact are nearly as large as the sheets which are being handled. FIG. 3 is a view partially in section of one of the nozzles 18. It will be seen that the under surface of the nozzle has an annular air passage 28 formed between a core piece 30 held in position on a spider 32 in spaced relation to the surrounding curved surface 34. Air admitted under pressure from the manifold is therefore directed outwardly along the plane of the lower surface of the nozzles as indicated by the arrows in this figure.

Referring again to FIG. 1, for a description of the operation of the apparatus, the sheets 14 are individually advanced along the conveyor 12 from a remote point toward the stack receiving means 10. As each sheet on the conveyor passes beneath the nozzles 18, the decrease in pressure between the sheets and the nozzles due to the increase in fluid velocity therebetween results in the sheets being picked up and held in closely spaced non-contacting relation to the nozzles as shown by the sheet 14A in FIG. 1. Due to the fact that the plane of the nozzles is lightly inclined to the horizontal (an inclination of as little as 2° is sufficient), the thus elevated sheets have a strong tendency to "slide downhill" toward the stack receiving means until they reach the position indicated by the sheet shown in 14B in FIG. 1. At this point, by means to be hereinafter described, the valve 26 is momentarily closed thus cutting off the supply of fluid to the manifold 20A and the sheet drops from the position of 14B onto the uppermost sheet of the stack. Its fall is vertical and is cushioned by the blanket of air trapped between the under-surface of the sheet 14B and the uppermost sheet on the stack.

One possible means for automatic operation of the valve 26 is illustrated in FIGS. 1 and 2. A four way valve 36 is connected to supply fluid pressure selectively to opposite ends of the cylinder 38 to operate the linkage 40 which interconnects the valve 26 with the piston in the cylinder 38. The valve 36 in turn is controlled by sensors 42, 44 and 46 shown most clearly in FIG. 2. These sensors are triggered by the arrival of a sheet at the position indicated at 14B in FIG. 1 and are effective to momentarily reverse the valve 36 to momentarily close the valve 26 and permit the sheet to drop onto the stack.

The vertical spacing between the sheets still on the conveyor belt and the under surface of the nozzles is not particularly critical which makes the system particularly attractive from a practical point of view. The partial vacuum created by the nozzles is sufficient to lift a sheet, for example, a glass sheet 6mm thick through a 1cm spacing and attract it toward the under surface of the nozzles. In its supported position the air film between the upper surface of a sheet and the under surface of the nozzles is between about 0.5 and 1.5 mm in thickness. Nozzle size, of course, is dependent on the minimum size of the sheets being handled. In one em-

bodiment, nozzles covering an area 150mm by 150mm have been effective to handle sheets as small as 300 by 300mm.

Referring lastly to FIG. 4, this merely diagrams one means for maintaining the vertical elevation of the uppermost sheet of the stack. It is of course, essential that this elevation be rather closely controlled so that the free fall distance of sheets from the nozzles to the top of the stack is substantially constant. As shown in FIG. 4, the stack is supported by a piston 50 extending out of a fluid pressure cylinder 52 and the position of the piston within the cylinder is under the control of the valve 54. A light source 56 is positioned to reflect light at a low angle from the upper surface of the uppermost sheet on the stack to a pair of photoelectric cells 58 and 60. If the stack is too high, the photocell 58 is activated to shift the valve 54 to admit fluid to the upper portion of cylinder 52 to lower the stack. Any "overshoot" of the support is then detected by the photocell 60 to reverse the process. When the height is correct, the reflected light beam will be centered with respect to the two photocells and the valve 54 will remain in a neutral position.

From the foregoing, it will be apparent to those skilled in this art that there is herein shown and disclosed a new and useful sheet material handling stacking apparatus and while a preferred embodiment has been illustrated and described, applicant claims the benefit of a full range of equivalents within the scope of the appended claims.

I claim:

1. A sheet stacking apparatus comprising in combination:
 a stack receiving means;
 conveying means for conveying sheets one at a time from a remote point to a station adjacent said receiving means;
 a manifold having a plurality of nozzles on the under surface thereof, positioned to overlie at least a sheet length of said conveying means as well as at least a portion of said stack receiving means, said nozzles being arranged to direct fluid under pressure from said manifold along the upper surface of sheets on said conveyor in order to elevate sheets from said conveyor toward said nozzles and maintain them in closely spaced but non-contacting relation to said nozzles, said nozzles lying in a common plane which is inclined to the horizontal with that end remote from said stack receiving means at

50

the highest elevation so that sheets suspended beneath said nozzles will slide downhill toward said receiving means;

means for supplying fluid under pressure to said manifold; and

means for momentarily cutting off the flow of air to selected ones of said nozzles positioned over said receiving means to permit sheets to drop vertically on to said stack receiving means.

2. Apparatus as defined by claim 1 in which said last mentioned means is a valve and in which said stack receiving means includes means responsive to the proximity of an approaching sheet for operating said valve.

3. Apparatus as defined by claim 1 including means responsive to the accumulation of sheets on said receiving means to progressively lower the said receiving means whereby the upper surface of the stack remains at substantially the same elevation.

4. Apparatus as defined by claim 3 including hydraulic means for supporting said stack and photoelectric means for sensing the height of the stack and connected to control said hydraulic means for maintaining a constant vertical weight of the stack.

5. In a sheet stacking device of the type including a means for accumulating and maintaining a constant elevation of the uppermost sheet in the stack, and a conveyor for advancing sheets one at a time from a remote point to a point adjacent the said means, apparatus for transferring sheets from said conveyor to the stack comprising in combination:

a plurality of fluid directing nozzles lying in a common plane, overlying at least a sheet length of said conveyor and at least a portion of said stack said plane being inclined downwardly toward said stack;

manifold means communicating with said nozzles; means for supplying fluid under pressure to said manifold, said nozzles being configured to direct fluid downwardly and along the upper surface of sheets on said conveyor to elevate sheets into close but non-contacting relation to said nozzles and permit the thus elevated sheets to slide downhill toward said stack; and

means responsive to a sheet being positioned over the stack to momentarily stop fluid flow to those nozzles then holding the sheet to permit it to fall by gravity to the upper surface of the stack.
